UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A MITER-PIECE FOR METALLIC CEILINGS.

SPECIFICATION forming part of Design No. 23,054, dated February 6, 1894.

Application filed January 8, 1894. Serial No. 496,200. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for a Miter-Piece for Metallic Ceilings, of which the following is a specification, reference being had to the accompanying drawing, forming part hereof,

5 which shows a miter-piece for metallic ceilings designed according to my invention.

My design consists of a miter piece for metallic ceilings which is leaf-shaped and curved and tapered from its larger or stem end toward its outer end. In the central line of the 15 miter there is a series of pyramidal projections A, which gradually decrease in size from the larger end toward the smaller end, or point, X. The longitudinal or side edges of the leaf 20 are serrated at B, as shown, and these serrations form parts of the "segments" of the compound leaf. The "segments" have ob-

long depressions b, bounded by ribs or ridges b'. At the larger end of the leaf there are scroll-shaped ridges C, and at the end of the 25 series of pyramidal projections A, there is an inclined diamond-shaped base D, from opposite sides of which project inclined sides E, the outer edges of which communicate with triangular-shaped pieces F, projecting from 30 the sides E at an angle.

The essential feature of my design is a leaf-shaped miter piece having serrated edges and a series of central pyramidal projections.

I claim—

35 The design for a miter piece herein shown and described.

In testimony whereof I have hereunto subscribed my name.

WILLIAM S. GRAFTON.
